UNITED STATES PATENT OFFICE.

EDGAR L. WILLIAMS, OF PEORIA, ILLINOIS, ASSIGNOR TO THE ARCHARENA COMPANY, OF SAME PLACE.

DESIGN FOR A GAME-BOARD.

SPECIFICATION forming part of Design No. 33,396, dated October 16, 1900.

Application filed July 14, 1900. Serial No. 23,679. Term of patent 14 years.

To all whom it may concern.

Be it known that I, EDGAR L. WILLIAMS, a citizen of the United States, residing at Peoria, in the county of Peoria and State of Illinois, have invented and produced a new and original Design for a Game-Board; and I do hereby declare that the following is a full, clear, and exact description of the invention, which will enable others skilled in the art to which it appertains to make and use the same.

This invention relates to a new design for game-boards.

In the accompanying drawing, which forms part of this application, the game-board is illustrated, having my design shown thereon.

The reference-letter A indicates the body of the board, which is square in outline and has a single border-line near its edge extending around all four of its sides, leaving a small clear space between said line and the edge of the board. An inner square is formed by a line C, parallel with the square just described. The center space within the square C is per-

fectly plain and is without markings of any kind. The square border left between the squares B and C is filled with pictures of birds of various kinds—such, for instance, as tropical birds and those found in temperate and frigid zones—such, for instance, as the parrot and ostrich for the torrid zone, the owl and turkey for the temperate zone, and the eider-duck for the frigid zone. The birds are arranged one above the other, and every second one faces in an opposite direction to the others, and all are shown in a state of rest, some being shown on perches and others standing upon the ground.

I claim—

The design for a game-board substantially as herein illustrated and described.

In testimony whereof I affix my signature in presence of two witnesses.

EDGAR L. WILLIAMS.
